United States Patent Office

Des. 199,310
Patented Oct. 6, 1964

199,310

CLOTHESPIN

Leandro P. Rizzuto, 7521 Ave. W, Brooklyn 34, N.Y.

Filed Oct. 21, 1963, Ser. No. 77,050

Term of patent 14 years

(Cl. D17—6)

Fig. 1.

Fig. 2.

Fig. 3.

Fig. 4.

FIG. 1 is a top plan view of a clothespin, showing my new design;

FIG. 2 is a front elevational view;

FIG. 3 is an end view looking at the left side of FIG. 2; and

FIG. 4 is an end view looking at the right side of FIG. 2.

I claim:

The ornamental design for a clothespin, substantially as shown.
